COMBINATION STORM SHUTTER AND AWNING

Clayton R. Reiner, Coral Gables, Fla.

Application November 10, 1950, Serial No. 195,013

6 Claims. (Cl. 160—129)

1

This invention relates to windows, and more particularly to a combined storm shutter and awning for use with windows.

The object of the invention is to provide a combined foldable storm shutter and awning for windows that can be easily and quickly operated from within a building, so as to provide protection from sun, storms, fire, burglary and the like.

Another object of the invention is to provide a combination storm shutter and awning for a window which provides an awning when in raised position, and which provides a shutter when in lowered position, the device of the present invention being easily installed and ruggedly constructed.

A further object of the invention is to provide a combined storm shutter and awning which is extremely simple and inexpensive to manufacture.

Other objects and advantages will be apparent during the course of the following description.

In the accompanying drawings forming a part of this application, and in which like numerals are used to designate like parts throughout the same:

Figure 1 is a front elevational view of a conventional window, having the assembly of the present invention attached thereto, the assembly being in raised position so as to provide an awning;

Figure 2 is a sectional view taken on the line 2—2 of Figure 1;

Figure 3 is a view similar to Figure 1, illustrating the device in the "closed" position to provide a storm shutter;

Figure 4 is a sectional view taken on the line 4—4 of Figure 3;

Figure 5 is an enlarged, vertical, detail, sectional view showing the guide track at its junction;

Figure 6 is an enlarged, detail, sectional view illustrating the track construction;

Figure 7 is a view similar to Figure 6, but illustrating the construction of the shutters or curtains at their joined ends.

Referring in detail to the drawings, there is shown a window which includes an upper section and a lower section 11, Figure 1, and a rectangular frame 12 is adapted to be secured to the window in any suitable manner. The present invention is directed to a combination storm shutter and awning, and the assembly of the present invention includes a pair of similar guide elements 14 which are arranged in spaced, parallel relation with respect to each other. Since

2

each of the guide elements 14 has the same construction as the other, a description of one will suffice for both. Each of the guide elements 14 may be fabricated of a suitable material, such as metal, and each comprises a flat body member 15 that may be secured to the frame 12 by suitable securing elements, such as screws 17. The screws 17 are adapted to be projected through apertured ears 16 that are formed integrally with, or secured to, the inner edge of the body member 15. Extending inwardly from the outer edge of the body member 15, and secured thereto, or formed integrally therewith, is a transverse flange 18, Figure 2. It will be seen from Figure 2 that the lower portion of the first flange 18 is straight, and this lower portion of the first flange 18 terminates in an arcuate or substantially triangularly-shaped upper portion.

Extending inwardly from the upper portion of the body member 15 and secured thereto is a second flange 19. The second flange 19 has a substantially triangular shape for a purpose to be later described.

Extending inwardly from the body member 15 is a third flange 20, and the third flange 20 is arranged in spaced, parallel relation with respect to a portion of the second flange 19. The third flange 20 coacts or cooperates with the second flange 19 to define a first track 21. Arranged in spaced, parallel relation with respect to the lower end of the first flange 18 and extending inwardly from the body member 15 is a fourth flange 22, the fourth flange 22 coacting with the lower straight portion of the first flange 18 to define a second track 23 for a purpose to be later described.

A partition or flange 24 extends between the parallel portions of the second flange 19 and the first flange 18, so as to define a double trackway. This double trackway includes a third track 25 which communicates with the first track 21, and a fourth track 26 which communicates with the second track 23.

The combination storm shutter and awning of the present invention further includes a pair of curtains or flexible blinds 27 and 28. Each of the curtains 27 and 28 has the same construction and each includes a plurality of parallel slats 29 which may be made of wood, plastic, metal or the like. A suitable flexible strip of fabric 30 serves to connect the slats 29 in each of the curtains 27 and 28 together, Figure 6. One end of each of the curtains 27 and 28 is connected together by a separator bar 31, Figures 5 and 7. The separator bar 31 can be connected to the pair of cur-

tains 27 and 28 in any suitable manner, as by nails, and carried by the separator bar 31 is a bushing 32. A cable or rope 33 has one end connected to the bushing 32, while a second cable 34 is also connected to the bushing 32 in any suitable manner. The other ends of the cables 33 and 34 extend into the building so that the position of the curtains 27 and 28 can be readily adjusted from within the building. A horizontally disposed guide rod 35 extends between the pair of guide elements 14 and is secured thereto in any suitable manner, as by welding. A bottom rail 36 extends between the lower ends of the side stiles 37 of the frame 12 and is secured thereto.

From the foregoing it is apparent that a combination storm shutter and awning has been provided. Thus, with the curtains in the position shown in Figures 1 and 2, a highly efficient awning is provided, and with the parts arranged as shown in Figures 3 and 4, a storm shutter is provided. To move the curtains from the position shown in Figures 1 and 2 to the position shown in Figures 3 and 4, the user merely pulls on the cable 34. This causes the curtain 21 to slide in the track 25 and also causes the curtain 28 to slide through the track 26. Continued pulling on the cable 34 causes the curtain 21 to enter the track 21, and also causes the curtain 28 to enter the track 23. Thus, the curtains will assume the position shown in Figures 3 and 4, so that a storm shutter is provided for the window, whereby the window will be protected from sun, storms, fire, burglary and the like. To return or move the parts from the position shown in Figures 3 and 4 to the position shown in Figures 1 and 2 so as to provide an awning, the user merely pulls on the cable 33. This pulling on the cable 33 causes the curtain 27 to slide from the first track 21 through the track 25, and also causes the other curtain 28 to slide from the second track 23 into the fourth track 26 until these members occupy the positions shown in Figures 1 and 2.

The curtains can be made of any suitable material, and it is to be noted that the pair of curtains or sections 27 and 28 are joined together by the separator bar 31. When the curtains are in their closed position, as shown in Figures 3 and 4, they provide a storm shutter, and when the curtains 27 and 28 are in their raised position, they provide an awning. The cable for actuating these curtains can be operated from within the house or other building. The type of rigging used can be varied as desired, or depending upon the type of window being serviced. The assembly of the present invention does not project out from the window very far, so that there will be a minimum resistance to wind, and the device is highly attractive in appearance. Also, it will be seen that the curtains extend from the house or other building wall in an upwardly floating direction, to thereby cause any water which collects thereon to readily drain therefrom. Also, the ease of opening and closing the device from within the house makes the invention especially advantageous, since a person does not have to leave the house in adverse weather conditions in order to adjust the awning or storm shutter. Also, the double construction of the guide elements 14 provides a rugged structure, and the doubled-up curtains 27 and 28 provide only half as much exposure to sudden gusts of wind. Any conventional winding device can be arranged in the house for opening and closing the curtains.

Further, the curtains can be made of any suit-

able material. Thus, the curtains can consist of or be made of two pieces of corrugated aluminum or other suitable flexible metal or substance, as well as a plurality of slats, as previously described.

I claim:

1. In a combined awning and storm shutter for a window a rectangular-shaped frame secured to the window and outlining therein said window, a pair of vertically disposed spaced parallel guide elements secured to the exterior of the frame, each of said guide elements including a first track and a second track in vertical alinement with each other, said first track having an outwardly curved lower end, said second track having an outwardly curved upper end, a double substantially triangular-shaped trackway extending forwardly of each of said guide elements and one of said trackways communicating with the curved lower end of said first track and the other of said trackways communicating with the upper end of said second track, a pair of curtains each having the outer edges thereof slidably arranged in said first and second tracks, and cables connected to each of said curtains for causing sliding movement of said curtains so that in raised position the curtains will be contained in the double trackways to provide an awning structure and in lowered position will be contained in said first and second tracks to provide a storm shutter.
2. In a combined awning and storm shutter for a window a rectangular-shaped frame secured to the window and outlining therein said window, a pair of vertically disposed spaced parallel guide elements secured to the exterior of the frame, each of said guide elements including a first track and a second track in vertical alinement with each other, said first track having an outwardly curved lower end, said second track having an outwardly curved upper end, a double substantially triangular-shaped trackway extending forwardly of each of said guide elements and one of said trackways communicating with the curved lower end of said first track and the other of said trackways communicating with the upper end of said second track, a pair of curtains each having the outer edges thereof slidably arranged in said first and second tracks, and cables connected to each of said curtains for causing sliding movement of said curtains so that in raised position the curtains will be contained in the double trackways to provide an awning structure and in lowered position will be contained in said first and second tracks to provide a storm shutter.
3. In a combined awning and storm shutter for a window a rectangular-shaped frame secured to the window and outlining therein said window, a pair of vertically disposed spaced parallel guide elements secured to the exterior of the frame, each of said guide elements including a first track and a second track in vertical alinement with each other, said first track having an outwardly curved lower end, said second track having an outwardly curved upper end, a double substantially triangular-shaped trackway extending forwardly of each of said guide elements and one of said trackways communicating with the curved lower end of said first track and the other of said trackways communicating with the upper end of said second track, a pair of curtains each having the outer edges thereof slidably arranged in said first and second tracks, and cables connected to each of said curtains for causing sliding movement of said curtains so that in raised position the curtains will be contained in the double trackways to provide an awning structure and in lowered position will be contained in said first and second tracks to provide a storm shutter, said curtains each comprising a plurality of slats and flexible strips connecting said slats together.
4. In a combined awning and storm shutter for a window a rectangular-shaped frame secured to the window and outlining therein said window, a pair of vertically disposed spaced parallel guide elements secured to the exterior of the frame, each of said guide elements including a first track and a second track in vertical alinement with each other, said first track having an outwardly curved lower end, said second track having an outwardly curved upper end, a double substantially triangular-shaped trackway extending forwardly of each of said guide elements and one of said trackways communicating with the curved lower end of said first track and the other of said trackways communicating with the upper end of said second track, a pair of curtains each having the outer edges thereof slidably arranged in said first and second tracks, and cables connected to each of said curtains for causing sliding movement of said curtains so that in raised position the curtains will be contained in the double trackways to provide an awning structure and in lowered position will be contained in said first and second tracks to provide a storm shutter.

movement of said curtains so that in raised position the curtains will be contained in the double trackways to provide an awning structure and in lowered position will be contained in said first and second tracks to provide a storm shutter, said curtains each comprising a plurality of slats and flexible strips connecting said slats together, and a horizontally disposed guide rod extending between said guide elements and secured thereto.

4. A combination storm shutter and awning for a window comprising a pair of spaced parallel guide elements, ears for attaching said guide elements to the window, each of said guide elements comprising a flat body member, a first flange extending inwardly from said body member at right angles thereto, a second flange of substantially triangular shape extending inwardly from said body member at right angles thereto and forming a continuation of said first flange, a third flange of substantially triangular shape extending inwardly of said body member at right angles thereto and arranged in spaced parallel relation with respect to said second flange to define a first track, a fourth flange of substantially triangular shape extending inwardly of said body member at right angles thereto and arranged in spaced parallel relation with respect to said second flange and coacting therewith to define a second track, a fifth flange extending inwardly of said body member at right angles thereto and in spaced parallel relation to said first flange and forming a continuation of said third flange to extend said first track between said first and fifth flanges, a sixth flange extending at right angles from said body member in vertical alinement with said first flange and forming a continuation of said third flange, a seventh flange extending from said body member at right angles thereto in spaced relation to said sixth flange and in vertical alinement with said fifth flange and forming a continuation of said third flange to extend said second track, a rod extending between said guide elements and secured thereto, a pair of flexible curtains having the opposite outer edges thereof slidably arranged in said first and second tracks, said curtains being positioned in the tracks within the second, third and fourth flanges to provide an awning when in their raised position, and said curtains being extended individually immediate the first and second flanges and the sixth and seventh flanges to provide a storm shutter when in their lowered position, a separator

bar arranged between adjacent ends of said curtains and connected thereto, a bushing carried by said separator bar, and a pair of pull cables connected to said bushing for imparting sliding movement of said curtains.

5. A combination storm shutter and awning for a window comprising a pair of spaced parallel guide elements, ears for attaching said guide elements to the window, each of said guide elements comprising a flat body member, a first flange extending inwardly from said body member, a second flange of substantially triangular shape extending inwardly from said body member, a third flange arranged in spaced parallel relation with respect to a portion of said second flange to define a first track, a fourth flange arranged in spaced parallel relation with respect to the lower end of said first flange and coacting therewith to define a second track, a partition arranged between said first flange and a portion of said second flange to define a double trackway that communicates with said first and second tracks, a rod extending between said guide elements and secured thereto, a pair of flexible curtains having the opposite outer edges thereof slidably arranged in said first and second tracks, said curtains providing an awning when in their raised position in said double trackway and said curtains providing a storm shutter when in their lowered position in said first and second tracks, a separator bar arranged between adjacent ends of said curtains and connected thereto, a bushing carried by said separator bar, and a pair of pull cables connected to said bushing for causing sliding movement of said curtains, said curtains each comprising a plurality of slats, and flexible strips connecting said slats together.

6. A combination storm shutter and awning as in claim 4 wherein said curtains each comprise a plurality of slats, and flexible strips are provided for connecting said slats together.
